UNITED STATES PATENT OFFICE.

EDMUND OCUMPAUGH, OF ROCHESTER, NEW YORK, ASSIGNOR TO
DEFIANCE MACHINE COMPANY, OF ROCHESTER, NEW YORK, A
CORPORATION OF NEW YORK.

CHECK-PRINTER.

No. 833,410.

Specification of Letters Patent.

Patented Oct. 16, 1906.

Application filed May 20, 1905. Serial No. 261,333.

To all whom it may concern:

Be it known that I, EDMUND OCUMPAUGH, a citizen of the United States, and a resident of Rochester, in the county of Monroe and State of New York, have invented certain new and useful Improvements in Check-Printers, of which the following is a specification.

This invention relates to check-printers; and it consists in the mechanism hereinafter described and claimed.

In the drawings, Figure 1 is a front elevation of a machine embodying this invention, the parts being broken away and parts being in sections in order to exhibit the internal construction. Fig. 2 is a vertical section on the line 2 2 of Fig. 1, showing the parts in the position preparatory to setting the printing. Fig. 3 is a vertical section on the same line of Fig. 1, showing the parts in the positions while making an impression. Fig. 4 is a top plan view of a part of the setting mechanism. Fig. 5 is a bottom plan view of the same mechanism. Fig. 6 is a cross-section on the line 6 6 of Fig. 4, and Fig. 7 is an enlarged plan of part of the gage-plate.

The mechanism has a base 1 and a cover 2. The cover is provided with a series of sight-holes 3 for reading the indicators. It is also provided with a gage-plate 4, hinged at 5 to the base 1 and normally held in one position by a spring 6. The setting-plate carries thumb-nuts 7, passing through slots 8 in the setting-plate, to which are connected rods 9, connected with stops 10 extending up through the slots therefor in said gage-plate, whereby the position of the check or other object to receive the impression may be adjusted in position with reference to the printing-line. The gage-plate 4 has also a slot or series of perforations 11 for a purpose to be described.

The sides of the case 2 are open, as at 12, Fig. 2, to permit the insertion of a check or object to receive the impression without limitation at the ends of the machine.

A series of movable type-blocks 13 are in the present form of the device in the form of bars, each bar having a consecutive series of type 14 on the upper face of the bar, and is

the form shown the said type may consist of a series of the digits from "1" to "9" and a zero. Each type-block is connected to a guide-block 15, sliding in a proper guideway upon the base 1 of the machine. This guideway may be constructed, as shown in the figures and particularly in Fig. 6. In each type-bar a groove is cut from front to back in the upper face of the bed or base 1, said groove having a vertical face 16 and a diagonal face 17, the diagonal face being broader at the bottom than at the top. The type-block 13 is broader than the top of said groove or slot and is attached to or forms part of the guide-block 15, under which is a bar 18, carried by and movable with the guide-block and capable of lateral motion with reference thereto. The bar 18 has diagonal slots, and headed pins passing through said slots hold the bar and block together. A setting-handle 19 is provided for each type-block and in the present form of the device is on the rod 20, which extends through the front to the base and is connected to the type-block by a lug 21. On pulling out or pushing in the handle 19 the type-block is set to its desired position.

An indicator is provided to show the setting of each type-block. It consists of a band or strip 22, connected to the type-block and passing around an idler-pulley 23 and thence to a spring-actuated drum 24, to which the end of the band or strip is fastened. On the surface of the band or strip are marked the same series of digits and zero as are upon the type-block to which the strip or band is attached. The spring-actuated drum tends to move the type-block and the band or strip into the normal position of rest, which may be adapted for the exhibition and imprinting of a line of zeros or may be for the exhibition of a line of blanks through the sight-orifices 3, and without the setting of any type to the printing-line.

A convenient construction of the spring-actuated drum embodies a stationary shaft 25, upon which the series of said drums are mounted, a coil-spring 26, fastened to or in said stationary shaft at one end and fastened at the other end to the drum, so that the

tendency of the spring is to wind up the drum and to pull the type-block 13 to its most retracted position, as shown in Fig. 2.

It is obvious that upon operating the setting device 19 any desired type block or blocks may be set to place any desired digit at a printing-line and that this movement of the printing-block will move with it the indicator and display at the sight orifice or orifices a numeral or numerals corresponding to the numeral or numerals on the type-blocks set at such printing-line.

In order to hold any or all of the type-blocks accurately at the printing-line, a retaining mechanism is employed, and means are also provided for releasing any one type-block and also means for releasing all the type-blocks simultaneously, so that they shall be retracted to their positions of rest by the spring 26 in the corresponding drum or drums. Each guide-block 15 has in one edge a series of ratchet-teeth 27, and upon the base adjacent to such teeth of each type-bar is a spring-actuated dog or pawl 28. The ratchet-teeth are at such a distance apart that each tooth when abutting against the dog holds a particular type upon the type-block in the exact printing position under the pull of the spring 26. Each of the dogs or pawls 28 has a pin 29, that projects into a slot or notch 30 in a transverse bar 31 extending across the machine, so that said bar 31 when moved releases all the pawls 28 from the notches of their type-bars, and the type-bars are retracted to their positions of rest. This is the means of resetting all the type-bars simultaneously to the position of rest.

The means of releasing individual type-bars without releasing any others is the following: The bar 18 above mentioned is slotted diagonally to its length, and through the slot 32 there is a pin 33, passing into the guide-block 15. (See particularly Figs. 4 and 5.) One edge 34 of each bar 18 rests against the pin 29 and its corresponding pawl, and the said bar 18 is operated by means of a rod 35 extending into convenient position and most conveniently passing through the center of the rod 20 and out through the handle 19. On holding the handle 19 and pressing inward the button 36 the bar 18 will be moved relatively to the guide-block 15, and by reason of the diagonal slotting the bar will be moved against the pin 29 of the pawl 28, and thus said pawl will be removed from the ratchet, and the parts are moved back to the position of rest by the turning of the spring 26.

Transversely through the case passes a shaft 37, which carries upon a curved arm 38 an inking-roller 39 for inking the respective type-blocks. The shaft also carries one or more impression-cams 40. A handle 41 outside the case operates the shaft, together with the inking-rollers and the impression-cam or

cams. A spring 42, or, preferably, more than one spring, attached to the case and also to a part movable with said shaft, tends to reset these parts to the non-operative position in which the inking-roller is ready for inking the type-blocks and the impression-cam or cams are out of operative position. A platen 43 is hung upon one or more arms 44, pivoted in the case and normally moved out of printing position by a spring 45. The platen 43 may have a removable impression-block 46 upon its printing-face, which projects through the slot or slots 11 in the gage-plate 4. The platen may also have an antifriction-roller 47 for engagement with the operating surface of each of the cams 40. If desired, also, an ink-storage roller 48 is set in the case in suitable position to engage or roll upon the surface of the inking-roller 39 when the latter is out of inking position. The supply-roller 48 may be hung upon an arm 49, pivoted to the case, and the axis 50 of the roller may pass out through a slot 51 in the side of the case, so that the roller 48 may be revolved when in contact with the roller 39 and may be moved to and from such contact.

The operation of the device is as follows: On pulling out the slotted knobs or handles 19 to the proper degrees the pawls 28 will engage in the ratchets 27, and under the tension of the springs 26 the printing-bars 13 corresponding to the operated handles will be adjusted so that the type upon them will be set to the printing-line, and at the same time the numerals or characters corresponding to those set at the printing-line will be displayed by the indicators through the sight-holes 3. The check or object upon which the printing-impression is to be received is laid face down upon the gage-plate 4 and is then pushed forward into the slot 12 until it is stopped by the stops 10, which have previously been adjusted, so that the printing will occur in such position upon the check or object to receive the impression as is desired. After this placing of the check in position the handle 41 is brought forward and downward, thus moving the arm 38 backward and causing the roller 39 to roll over the type on the type-bars at the printing-line and ink them. After the inking-roller has passed backward away from the type that it has inked the cams 40 act upon the platen 43 and cause it to swing around its pivot and to depress the gage-plate 4 until it makes contact with the type-blocks and then to press the check or object to receive the impression through the orifice or orifices 11 upon the faces of the inked type beneath, thus producing the impression. Upon releasing the handle 41 its spring 42 throws it from the position shown in Fig. 3 to that shown in Fig. 2. At the same time the platen-arm 44 rises to the position in Fig. 2 and the gage-plate 4 returns

under the influence of its spring to the position in said Fig. 2. Then pressure upon the end of the setting-bar 31 moves the pawls 28 from the racks 27, and by the pull of the springs 26 all the type-bars are returned to their positions of rest. (Shown in Fig. 2.)

What I claim is—

1. In a check-printer, a series of spring-actuated drums, a series of flexible bands, each connected at one end to a drum, one of each pair of said parts carrying indication-marks, and a series of movable type-bars, one connected to the other end of one of the bands, whereby movement of the type-bar causes indication and the type-bar is returned to its initial position by the spring-actuated drum.

2. In a check-printer, a series of settable type-carriers, a platen movable to and from said type-carriers, a cam for actuating said platen also an inking-roller for inking the type on said type-carriers and a single rock-shaft to which the cam and the roller are attached.

3. In a check-printer, a series of settable type-carriers, a platen movable to and from said type-carriers, a shaft bearing a cam for actuating said platen, an inking-roller for inking the type on said type-carriers, and a gage-plate having stops therein for determining the position of the object to receive the impression and movable with said platen to the printing position.

4. In a check-printer, a spring-retracted type-carrier, movable in a predetermined path and having a ratchet-rack whose teeth determine the printing positions of the type upon said type-carrier, a stationary spring-dog for engaging said rack, and means carried by said rack for releasing said dog for retracting said type-carrier.

5. In a check-printer, a spring-retracted type-carrier having a ratchet-rack thereon, a stationary dog for engaging said rack, and a bar carried by said rack and movable laterally with reference thereto and, when moved laterally, adapted to engage and to release said dog from said rack.

6. In a check-printer, a series of spring-retracted type-carriers, each movable in a predetermined path and having a ratchet-rack whose teeth determine the printing positions of the type on said type-carrier, a stationary spring-dog for engaging each rack; means for releasing all said dogs simultaneously, and separate means for releasing each dog.

7. In a check-printer, a series of spring-actuated drums, a series of flexible bands, each one of which is connected at one end to one of the drums, one of each pair of said parts carrying indication-marks, a series of movable type-bars each connected to the other end of said bands, whereby the movement of the type-bar causes indication and

the type-bar is retracted by the drum, and means for retaining the type-bar in different set positions.

8. In a check-printer, a settable type-carrier, a platen movable to and from said type-carrier, a gage-plate movable with said platen, means for actuating said platen, an inking-roller and means for moving said inking-roller underneath said gage-plate for inking the type on said type-carriers, and for moving said roller from under said gage-plate as the platen moves to the printing position.

9. In a check-printer, a frame, a spring-retracted type-carrier movable in a predetermined path in said frame, a ratchet-rack on one of said parts whose teeth determine the printing positions of type upon said type-carrier, a dog upon the other of said parts for engaging said rack and holding the type-carrier in a printing position, means movable with said type-carrier for disengaging said dog and rack, and means for causing engagement thereof.

10. In a check-printer, a frame, a spring-retracted type-carrier having a series of type and movable in a predetermined path in said frame, a ratchet-rack upon one of said parts whose teeth determine the printing positions of type upon said type-carrier, a dog for engaging said rack, a handle for setting said type-carrier, means carried by and movable with said handle for disengaging the dog and rack, and spring means for causing engagement of the dog and rack.

11. In a check-printer, a frame, a spring-retracted type-carrier having a series of type thereon and movable in a predetermined path in said frame, a movable ratchet-rack on the type-carrier whose teeth determine the printing positions of type upon said type-carrier, a dog upon the frame for engaging said rack and holding the type-carrier in a printing position, a spring for actuating said dog, and means movable with said type-carrier for disengaging said dog from said rack against the force of the spring, whereby the type-bars may be set while the dogs are withdrawn and are locked in place by releasing the dogs.

12. In a check-printer, a series of spring-actuated drums, a series of flexible bands each connected at one end to a drum, one of each pair of said parts carrying indication-marks and a series of movable type-bars, one connected to the other end of one of said bands, whereby the positions of the type-bars are indicated and they are returned to their initial positions, means for setting each type-bar, and means for releasably holding each type-bar in its set position.

13. In a check-printer, a series of spring-actuated drums, a series of flexible bands each connected at one end to a drum, one of

each pair of said parts carrying indicating-
marks and a series of movable type-bars, one
connected to the other end of one of said
bands, whereby the positions of the type-
bars are indicated and they are returned to
their initial positions by the spring-actuated
drums, means for setting each type-bar,

means for holding each type-bar in its set po-
sition, and means for holding said holding
means out of operation.

EDMUND OCUMPAUGH.
